HYDROSTATIC WEIR SHUTTER

Filed June 13, 1927

Inventor:

Franťošek Jermář.

UNITED STATES PATENT OFFICE.

FRANTIŠEK JERMÁŘ, OF OPAVA, CZECHOSLOVAKIA.

HYDROSTATIC WEIR SHUTTER.

Application filed June 13, 1927, Serial No. 198,594, and in Czechoslovakia February 14, 1927.

Hydrostatic weir shutters usually require, owing to the considerable lateral extension of the flaps as compared with the vertical adjustability of the shutter, a very wide and costly substructure.

The object of the present invention is to produce a hydrostatic weir shutter wherein the lateral extension of the flaps but little exceeds the vertical adjustability of the shutter, and the invention consists in the provision of two hingedly connected shutter plates supported like a roof structure on two horizontally hinged flaps turned in opposite directions and located in hydrostatic chambers.

The accompanying drawing represents a cross-section of the weir and shows the shutter in fully extended position.

The substructure 8 is formed with two hydrostatic chambers 7 and 7^a which can each be connected through channels 9 and 9^a respectively and by means of the usual controlling devices, either with the high or with the low water. Pivoted horizontally at 6 and 6^a to the substructure between the two chambers, are two flaps 5 and 5^a which are preferably sector-shaped and buoyant and which are oscillated by fluctuations in the water pressure. Two shutter plates 1 and 1^a, which are pivoted together at 3, are pivoted at 4 and 4^a respectively to the free ends of the flaps 5 and 5^a so as to form a roof-shaped structure which determines the level of the water head in the upper pool. The flaps are adapted to sink by gravity into the chambers in opposition to the pressure produced by the low water pool. The highest water level is obtained when the chambers 7 and 7^a are both connected to the upper pool, the elements having then the position shown by full lines in the drawing. If one of the chambers, for instance 7, is cut off from the upper pool and set in com-

munication with the lower pool, the flaps 5 will be lowered into the position shown by 45 the dotted lines 5^b, and the shutter plates will take up the position shown by the dotted lines 1^b and 1^c. To lower the shutters still further the communication of the chamber 7^a is also changed from the upper 50 to the lower pool so as to allow the flap 5^a to drop into the position shown at 5^e, the shutter plates being then lowered to the positions 1^d and 1^e. For raising the shutter, the chambers are again set in communication 55 with the upper pool either one at a time or simultaneously.

In this arrangement the shutter plates 1, 1^a are comparatively short and the chambers 7 and 7^a very shallow. The width of 60 the shutter, moreover, is only 1.5 times more than the full height H of the same above the substructure, as shown by the arrows. In existing shutters the width is usually 3.5 times that of the full height.

I claim:

1. A hydrostatic weir shutter comprising a substructure having two hydrostatic chambers arranged in juxtaposition, flaps arranged in said chambers and adapted to 70 swing in vertical planes about axes situated at the adjacent sides of the chambers, and shutter plates hinged together and to the free ends of the flaps so as to form a roof-shaped structure which can be raised 75 and collapsed by means of the flaps.

2. A structure as claimed in claim 1 wherein the flaps are sector-shaped and buoyant.

3. The structure claimed in claim 1 in 80 combination with means for setting either chamber independently in communication either with the lower or with the upper pool.
